LOOM TEMPLE

William H. Bahan, Greenville, S. C.

Application November 3, 1939, Serial No. 302,745

2 Claims. (Cl. 139—303)

This invention relates to a loom temple and more especially to an apparatus associated with the thread cutter so as to insure longer wear and more efficient operation.

5 In the manufacture of cloth, loom temples are employed at the selvages to keep the cloth properly stretched transversely thereof. Usually there is associated with the loom temple, a thread cutter for clipping the loose ends of the warp thread 10 at a point adjacent the selvage. This thread cutter operates upon each pick of the loom, but it is only when a transfer of a bobbin is effected that a loose end is present for the cutter to shear.

The conventional thread cutter is positioned 15 in the temple head so as to have reciprocatory movement, with the bottom of the cutter slidably engaging a very narrow bearing surface on the bottom of the temple head. The thread engaging points or prongs associated with each cutter 20 normally project forwardly beyond the confines of the head to a thread engaging position. When the thread is to be sheared, of course, the points are withdrawn within the temple head. In order to provide a compact assembly, these prongs are 25 notched so that the necessary clearance between the temple roll pin and the prongs is present. Also the foremost extremities of the prongs barely clear the bottom of the temple head when the thread cutter is in retracted position. As a result 30 of the combined above-named features, the bearing surface of the thread cutter soon becomes worn, resulting in the notched portion, on the free ends of the thread cutter engaging the top of the temple roll pin and severing or partially 35 severing it. At the same time, the lower ends of the thread cutter are allowed to dig into the upper surface of the bottom piece, which action often results in inefficient operation as well as frequent breakage and replacement of parts.

40 It is therefore an object of this invention to provide a supplementary bearing surface for a temple thread cutter which is constructed in such a manner and of such a material that the free end of the cutter will not be allowed to cut into the temple roll pin or to dig into the bottom temple piece.

45 It is another object of this invention to provide an apparatus of the class described having means for adjusting the lowermost position to which the free end of the thread cutter can move.

50 It is a further object of this invention to provide a novel thread cutter comprising a lay engaging portion having a pair of thread engaging points secured to one end thereof, which points are formed from a U-shaped plate which in turn 55 partially encircles the exterior of one end of the lay engaging member. This method of constructing the thread cutter has a decided advantage because the U-shaped points are now constructed in one piece instead of two as has been previously

the case. Also by providing the U-shaped points, the three sides of the lay engaging member are encircled and therefore only one rivet is necessary for securing the points to the lay engaging member.

5 Some of the objects of the invention having been stated, other objects will appear as the description proceeds when taken in connection with the accompanying drawings, in which—

10 Figure 1 is a plan view of a temple head showing a fabric engaged thereby and my invention associated therewith;

Figure 2 is an elevation looking at the near side of Figure 1;

15 Figure 3 is a vertical sectional view taken along the line 3—3 in Figure 1, but showing the thread cutter in retracted position;

20 Figure 4 is an isometric view of the supplementary bearing bracket which is used in conjunction with the thread cutter;

25 Figure 5 is an isometric view looking at the opposite side of the supplementary bearing bracket from that shown in Figure 4;

Figure 6 is a top plan view of a temple head showing a slightly modified form of the invention;

30 Figure 7 is an elevation looking at the near side of Figure 6;

Figure 8 is an exploded isometric view of the supplementary bearing and adjusting brackets apart from the temple head;

35 Figure 9 is an isometric view of the thread cutter which is employed in connection with the temple head;

Figure 10 is an inverted exploded isometric view 35 of the thread cutter parts.

Referring more specifically to the drawings, the numeral 10 denotes a temple bar having integral therewith a lower temple head piece 11 to which is secured a top temple head piece 12 by any suitable means such as a bolt 14. A temple roll 15 40 is rotatably confined between the members 11 and 12 by any suitable means such as temple roll pins 16 and 17. This temple roll serves to grip the selvage of the cloth and effect the proper 45 transverse tension during weaving. It is seen that the cloth comprises warp threads 18, filling threads 19. As heretofore stated, when a transfer of a bobbin is made into a shuttle a loose end is left extending beyond the selvage of the cloth 50 and therefore means must be provided for severing it. In the textile industry, various and sundry types of temple thread cutting mechanisms have been employed, most of which are operated upon each pick of the loom, but since an end is not 55 directed into engagement with the cutter except upon a transfer, there will be quite a few picks between cutting operations. Nevertheless, due to the reciprocation of the lay, the thread cutter is maintained in constant operation, which results 60

in wear between the lower side thereof and the upper side of the bottom temple piece 11.

In this invention a supplementary bearing surface is provided so as to reduce to a minimum the amount of wear that takes place. Between the bottom portion 11 and the top portion 12, a thread cutter 21 is adapted to reciprocate, said thread cutter having a downwardly extending portion 22 which is engaged by the lay of the loom upon each pick, and a horizontally projecting portion 23, the lower side of which is adapted to slidably contact bearing portion 24 of supplementary bearing bracket 25. This bearing member 25 has a hole 26 therein which is penetrated by the temple roll pin 16. Also a set screw 27 is provided in the vertical sidewall of the member 25 in such a position that its end can be forced into contact with the exterior of the temple head to hold the portion 24 adjusted at the desired elevation. It is preferable to form a member 25 out of a case-hardened material in order to eliminate as much wear as possible. Figure 3 shows plainly the amount of added bearing surface which is given to the lower edge of portion 23 of the thread cutter. In the conventional loom temples, the slot 28 as shown in this figure is always present, leaving a very short supporting surface when the cutter is in retracted position.

The free end of the thread cutter 21 has a pair of points 29 and 30 secured thereto by any suitable means such as a rivet 31. Figures 9 and 10 show the detailed structure of these points and their associated parts. It is here seen that the points are made of one piece of plate material which is bent in a substantially U-shaped manner and having a connecting bridge 33 between parallel walls. This bridge portion 33 fits into a notch 34 cut in the end of portion 23 whereas the adjacent wall portions of the bridge member 33 fits against the opposed sides of portion 23 so that the outer surfaces of member 23 and portions 29 and 30 will be flush. The points 29 and 30 have holes 37 therein which coincide with hole 38 in the end of portion 23, said holes being penetrated by the rivet 31 heretofore described. In order to provide the necessary clearance between the points 29 and 30 and the temple roll pin 16, a suitable notch 40 is cut in the lower sides of the points.

When the thread cutter is installed in the manner shown in Figures 1, 2 and 3, a suitable torsion spring 41 is provided said spring having one end thereof encircling a pin 42 and its other end encircling a pin 43 on portion 22 of the thread cutter. This spring is adapted to normally force the ends of points 29 and 30 to an extended position (Figure 2) beyond the confines of the temple head. As the lay engages the downwardly projecting portion 22, the prongs 29 and 30 are withdrawn to the interior of the temple head from the position shown in Figure 2 to the position shown in Figure 3. It is here seen that the prongs are disposed upon each side of a suitable shearing knife 45 within the temple head. If upon a withdrawal, there is a thread engaged by the points 29 and 30, it is immediately sheared.

It is therefore seen that the additional bearing surface provided by the portion 24 of supplementary bearing bracket 25 will decrease the wear between the bottom edge of portion 23 of the thread cutter and therefore prevent the points 29 and 30 from cutting into the temple roll pin 16 or from engaging the upper surface

of the bottom temple piece 11 and causing breakage. As a rule the temple pieces 11 and 12 are made of cast iron which wears very easily, so by providing a piece of hardened material as a supplementary bearing surface, the amount of wear can be materially decreased.

Figures 6 and 7 show a slightly modified form of the invention in which like reference characters will be used to designate like parts. In this form of the invention, a supporting bracket 48 is provided, which is very similar to the bracket 25, previously described. A slightly different form of adjusting means, however, is provided. The bracket 48 has a portion 49 integral therewith which serves as a bearing surface in the same manner that the portion 24 in the preceding form serves. A hole 50 is disposed in member 48 which is penetrated by the temple roll pin 16 to secure the same to the temple head. In order to provide an effective means for adjusting the height of the bearing portion 49, an elongated rectangular slot 51 is provided which slot is penetrated by projection 52 of U-shaped member 53. This U-shaped member has another projection 54 integral therewith and parallel to the projection 52. A slot 55 is provided in the projection 54 which fits over the bolt 14a. This bolt 14a is also used for securing the top temple piece 12 to the bottom portion 11. A nut 58 is employed for holding the portions 11 and 12 together whereas another nut 59 is threadably secured on the upper end of bolt 14a to securely hold the bracket 53 on the bolt 14a. When it is desired to adjust the elevation of the member 53 and thereby fix the lowermost position to which the points 29 and 30 can move during the beat up stroke of the loom lay, it is only necessary to remove the nut 59 and place suitable shims or washers beneath the projection 54 and on top of the nut 58. The purpose of providing a slot 55 is to allow the member 53 to be moved inwardly or away from the bracket 48 as in the case of installation or removal of this member.

In the drawings and specification, there has been set forth a preferred embodiment of the invention, and although specific terms are employed, they are used in a generic and descriptive sense only, and not for purposes of limitation, the scope of the invention being set forth in the appended claims.

I claim:

1. In a loom temple having a raceway and a thread cutter mounted for reciprocatory movement therein, a wear plate secured to the temple and extending beneath the thread cutter for supporting the thread cutter in its movements, and a set screw mounted in the wear plate member and engaging the temple for allowing of adjusting vertically the position of the wear plate relative to the temple.
2. In a loom temple having a raceway and a thread cutter mounted for reciprocatory movement therein, a wear plate secured to the temple and extending beneath the thread cutter for supporting the thread cutter in its movements, a set screw mounted in the wear plate member and engaging the temple for adjusting vertically the position of the wear plate relative to the temple, said thread cutter having the thread engaging portion thereon made of one piece and fitting over and secured to the proximate end of the other portion of the thread cutter.
